UNITED STATES PATENT OFFICE.

DANIEL MURRAY, OF SALEM, MASSACHUSETTS.

THILL-COUPING.

SPECIFICATION forming part of Letters Patent No. 377,861, dated February 14, 1888.

Application filed October 19, 1887. Serial No. 252,847. (No model.)

To all whom it may concern:

Be it known that I, DANIEL MURRAY, a citizen of the United States, and a resident of Salem, in the county of Essex and State of Massachusetts, have invented new and useful Improvements in Thill-Couplings, of which the following, taken in connection with the accompanying drawings, is a specification.

This invention relates to improvements in thill-couplings, and it is carried out as follows, reference being had to the accompanying drawings, wherein—

Figure 1 represents a plan view of the invention. Fig. 2 represents a longitudinal section on the line A B, shown in Fig. 1. Fig. 3 represents a cross-section on the line C D, also shown in Fig. 1; and Fig. 4 represents a plan view of the shaft-iron.

Similar letters refer to similar parts whenever they occur on the different parts of the drawings.

a is the clasp, with its screws a' a' and nuts a'' a'', by means of which and the yoke b said clasp is firmly secured to the carriage-axle c, as usual.

In one piece with the clasp a is made the bearing-piece a³, having an upwardly-projecting annular shell, a⁴, made in one piece with or secured to said bearing-piece a³, as shown in Figs. 2 and 3.

d is the shaft-iron, secured by means of bolts or screws to the shaft, as usual. Said shaft-iron has a rear forked end, d', and in one piece with such forked end are made the trunnions d'' d'' and central ball, d³, as shown in the drawings. The annular shell a⁴ is cut away from the top downward at two diametrically-opposite places, as shown at a⁵ a⁵ in Fig. 3, as well as in dotted lines in Fig. 2, to permit the trunnions d'' d'' to be introduced therein when the ball d³ is placed within the said shell a⁴, as shown in Figs. 2 and 3. The interior upper portion of the shell a⁴ is screw-threaded, and into it is screwed firmly the plug e, the lower end of which is cup-shaped, as shown at e' in Figs. 2 and 3, corresponding to the ball d³, for which it serves as an upper bearing.

f is a detachable ring that is placed around the shell a⁴ after the ball d³ has been placed within the shell a⁴, and it serves to cover up the slits or openings a⁵ a⁵ in the sides of the

shell a⁴, thus preventing dust or grit from getting into the shell a⁴, as well as serving to retain the lubricant that is placed in said shell. After the said ring f has been placed in position, as shown in Figs. 2 and 3, the plug e is screwed in place, as shown in said figures, its flange e'' serving to hold the ring f in place. The under side of the ball d³ has its bearing in the cup g, which latter has a downwardly-projecting screw-threaded shank, g', that is adjustable in a screw-threaded perforation in the bottom of the bearing-piece a³, as shown in Figs. 2 and 3, said shank being preferably provided with a slit, g'', in its lower end, to enable it to be turned and adjusted by means of an ordinary screw-driver or equivalent tool.

g³ is a check-nut on the lower end of the shank g', for the purpose of securing the latter to the bearing-piece a³ after it has been adjusted. It will thus be seen that in the ratio as the ball d³ wears such wear is compensated by the vertical adjustment of the cup-bearing g, thus permitting the ball of the shaft-iron to work freely in its two cup-bearings without any rattling whatever.

Having thus fully described the nature, construction, and operation of my invention, I wish to secure by Letters Patent and claim—

1. In a thill-coupling, the clasp a and its bearing a³, having the shell a⁴ and cup-shaped plug e e', in combination with the shaft-iron d, having forked end d', trunnions d'' d'', and ball d³, and the adjustable cup-bearing g, having screw-threaded shank g' and check-nut g³, as and for the purpose set forth.

2. In a thill-coupling, the bearing-piece a³ and its shell a⁴, and the shaft-iron d, with its forked end d', trunnions d'' d'', and ball d³, in combination with the cup-shaped upper plug, e e', the inclosing ring f, and lower adjustable cup-bearing, g, having screw-threaded shank g' and check-nut g³, as and for the purpose set forth.

In testimony whereof I have signed my name to this specification, in the presence of two subscribing witnesses, on this 10th day of August, A. D. 1887.

DANIEL MURRAY.
